[57] CLAIM

The ornamental design for a hand pendant with universal hanger/stand, as shown and described.

DESCRIPTION

FIG. 1 is a perspective view of the front and right side of a hand pendant with universal hanger/stand showing our new design;

FIG. 2 is a front view of the hand pendant with universal hanger/stand of FIG. 1;

FIG. 3 is a right side view of the hand pendant with universal hanger/stand of FIG. 2;

FIG. 4 is a back view of the hand pendant with universal hanger/stand of FIG. 2;

FIG. 5 is a bottom view of the hand pendant with universal hanger/stand of FIG. 2;

FIG. 6 is a top view of the hand pendant with universal hanger/stand of FIG. 2;

FIG. 7 is a right side view of the hand pendant with universal hanger/stand of FIG. 2 in a hanging position;

FIG. 8 is a right side view of the hand pendant with universal hanger/stand of FIG. 2 in a first standing position; and,

FIG. 9 is a right side view of the hand pendant with universal hanger/stand of FIG. 2 thereof in a second standing position.
